United States Patent

Des. 238,162

Patented Dec. 23, 1975

238,162

STORE

Joseph Binder, Oceanside, Michael J. Viesti, Bronx, and Carl Palestini, Lido Beach, N.Y., assignors to The Bohack Corporation, Brooklyn, N.Y.

Filed Aug. 16, 1972, Ser. No. 281,142

(Filed under Rule 47(a) and 35 U.S.C. 116)

Term of patent 14 years

Int. Cl. D25—03

U.S. Cl. D13—1 R

FIG. 1

FIG. 1 is a perspective view of the interior of the store of our invention looking towards the rear thereof, the roof or top, the front and one side of said store having been removed to facilitate the illustration of said store;

FIG. 2 is another perspective view of the interior of the store of our invention looking towards the front thereof, the roof or top of said store being removed to facilitate the illustration of said store; and

FIG. 3 is a perspective view of the exterior of the design for a store of our invention, looking towards the rear thereof.

What is claimed is:

The ornamental design for a store, as shown.
